UNITED STATES PATENT OFFICE.

GEORGE WILLIAM BELDAM, OF EALING, ENGLAND.

CRICKET, HOCKEY, AND LIKE BALL.

Application filed October 1, 1925, Serial No. 59,947, and in Great Britain October 30, 1924.

This invention has reference to balls of the kind used or for playing the game of cricket, hockey and similar games, which are used on wet ground, or under similar 5 conditions; and it has primarily for its object and effect to provide balls of this kind which are not so liable to be damaged by wet, or lose their normal quality under the conditions of play, or use.

10 In this ball, the core is enclosed within an outer cover of material such as gutta-percha, balata, rubber or rubber compound or like material, or a mixture of such materials—instead of leather which is usually 15 employed as the covering—which is applied by moulding it on to worsted or like soft material which forms the core, or outer layer of the core of the ball; that is the gutta-percha, balata or like outer cover 20 is pressed on to the soft core material, by which, and the application also of heat, a firm adhesion or amalgamation of the core and the covering of gutta-percha, balata, rubber, or rubber compound or the like, is 25 obtained.

This outer covering is according to one method of application applied in the form of two semi-spherical cups, and they are 30 placed over the core or body of the ball, and subjected to pressure and heat in suitable moulds.

A hard ball so constructed will be impervious to wet, and will keep its shape and 35 playing qualities under the circumstances as stated; and these qualities will be preserved for a relatively great length of time; and with regard to its re-action on the hockey stick, club or bat, the effect on the hands of the player is generally more pleasing than 40 with balls of ordinary construction.

The ball is very serviceable where it is subjected to hard wear, such as is required in a ball used for cricket and base ball practice, and under similar circumstances.

45 A ball made according to this invention is illustrated in cross section in the drawing.

In this drawing, 1 is the outer covering of gutta-percha, balata, rubber, or rubber compound or like material, or a mixture of 50 such materials; 2 is the covering of worsted or like material directly within it, which forms the outer part of the core, and within 55 which are other core laminæ 3 consisting of worsted or like quilts, and 4 consisting of cork and rubber, or similar compound or material; the latter being similarly applied

as the outer covering 1; i. e., by making each layer or cover 4 of two hollow semi-spherical cups of the size and diameter required, and applying them by pressure, or 60 pressure and heat, in the manner herein described.

Within the core parts 3, 4, is the centre or matrix spherical core 5, which may be cork and rubber or like material, or of any 65 suitable substance.

In manufacture, the cork and rubber, or like compound or material laminæ or parts 70 4, are, as stated, made of two hollow semi-spherical cups, and they are applied by placing them in semi-spherical moulds, with the central ball part within them, and then subjecting them to pressure of the required 75 intensity, such as is used in manufacturing golf balls, and also subjecting them to heat 80 by heating the moulds. After each pair of hollow cups is applied and compressed, a layer or covering 3 of worsted or the like, forming a quilt or blanket, is applied over them in any suitable known way; and then 85 the subsequent covering of the cork and rubber or like material 4 is similarly applied. Finally over the last covering 3, the outer cover of gutta-percha or the like rubber, or rubber compound or a mixture of 90 same is applied compressed under heat, as 95 above described.

By the outer covering, or the outer and inner coverings or laminæ being subjected to pressure in moulds of the required size, 90 and heat, the adjacent edges of the outer and core cups are joined or welded, and a firm adhesion or amalgamation of the outer cover 1, with the worsted or like core parts or quilts is obtained. After the ball is so 95 made it is vulcanized in the usual way of vulcanizing golf and similar balls.

In some cases the joining and compression of all the hemi-spherical cups may be effected at once, by one act of compression in 100 the moulds.

The proportion of thickness of the different coverings or laminæ shown in the drawings, is a suitable one.

The surface of the outer covering 1 may 105 be smooth, or slightly rough, or furnished with a suitable pattern.

What is claimed is:—

1. A ball comprising an inner spherical mass of cork and rubber and concentric 110 enveloping layers alternately of cork and rubber and worsted, the cork and rubber

layers being in semi-spherical hollow form and united at their edges subsequent to their application, the final layer being of a comparatively thin resilient character compressed under heat.

2. A ball comprising an inner spherical mass of cork and rubber and concentric enveloping layers alternately of cork and rubber and worsted, the cork and rubber layers being in semi-spherical hollow form and united at their edges subsequent to their

application, the successive layers of cork and rubber being of gradually increasing thickness toward the surface of the ball with the intervening layers of worsted of substantially the same thickness, the final layer being of a comparatively thin resilient character compressed under heat.

In testimony whereof I have signed my name to this specification.

GEORGE WILLIAM BELDAM.
